(57) **CLAIM**

The ornamental design for a sacro-iliac guide, as shown and described.

DESCRIPTION

FIG. 1 is a front perspective view of a sacro-iliac guide showing our new design;

FIG. 2 is a rear perspective view of the sacro-iliac guide illustrated in FIG. 1;

FIG. 3 is a front elevation view of the sacro-iliac guide illustrated in FIG. 1;

FIG. 4 is a rear elevation view of the sacro-iliac guide illustrated in FIG. 1;

FIG. 5 is a right side elevation view of the sacro-iliac guide illustrated in FIG. 1;

FIG. 6 is a left side elevation view of the sacro-iliac guide illustrated in FIG. 1;

FIG. 7 is a top plan view of the sacro-iliac guide illustrated in FIG. 1; and,

FIG. 8 is a bottom plan view of the sacro-iliac guide illustrated in FIG. 1.

The dash-dot broken lines immediately adjacent the shaded areas represent the bounds of the claimed design while dash broken lines are directed to environment and are for illustrative purposes only; the dash-dot broken lines and dash broken lines form no part of the claimed design.
